US0D1013881S

(12) **United States Design Patent** (10) Patent No.: **US D1,013,881 S**
(45) Date of Patent: ** Feb. 6, 2024

(54) **PNEUMATIC COMPRESSION DEVICE**

(71) Applicant: **Therabody, Inc.**, Los Angeles, CA
(US)

(72) Inventors: **Jaime Sanchez Solana**, Los Angeles, CA (US); **Brian Carberry**, Los Angeles, CA (US); **Brian Zeng**, Dongguan (CN); **Washington Alexander Silva Garces**, Los Angeles, CA (US); **William Webb**, San Francisco, CA (US); **Patrick Tufts**, San Francisco, CA (US); **Cale Kaufman**, Oakland, CA (US)

(73) Assignee: **Therabody, Inc.**, Los Angeles, CA (US)

(**) Term: **15 Years**

(21) Appl. No.: **29/875,500**

(22) Filed: **May 5, 2023**

Related U.S. Application Data

(62) Division of application No. 29/821,801, filed on Jan. 3, 2022, now Pat. No. Des. 987,832.

CLAIM

The ornamental design for a pneumatic compression device, as shown and described.

DESCRIPTION

FIG. 1 is a perspective view of a pneumatic compression device showing the claimed design;

FIG. 2 is a front elevational view thereof;

FIG. 3 is a rear elevational view thereof;

FIG. 4 is a right elevational view thereof;

FIG. 5 is a left elevational view thereof;

FIG. 6 is a top plan view thereof; and,

FIG. 7 is a bottom plan view thereof.

(Continued)

The broken lines in the figures show portions of the pneumatic compression device that form no part of the claimed design.

1 Claim, 6 Drawing Sheets
